Specification for Design.

Patented May 4, 1920.

Application filed September 28, 1915. Serial No. 53,132. Term of patent 7 years.

To all whom it may concern:

Be it known that I, HAROLD W. BENNET, residing at Evanston, in the county of Cook and State of Illinois, have invented a new, original, and ornamental Design for a Clock-Casing, of which the following is a specification, reference being had to the accompanying drawing, forming a part thereof.

Figure 1 is a front plan view of a clock casing showing my new design; and

Fig. 2 is a side view of Fig. 1.

I claim—

The ornamental design for a clock casing, as shown.

In witness whereof, I have hereunto subscribed my name.

HAROLD W. BENNET.
